UNITED STATES PATENT OFFICE.

JOSEPH D. HUNTINGTON, OF CHICAGO, ILLINOIS.

TOOL FOR FACING EMERY-WHEELS.

SPECIFICATION forming part of Letters Patent No. 288,628, dated November 20, 1883.

Application filed August 8, 1883. (No model.)

To all whom it may concern:

Be it known that I, JOSEPH D. HUNTINGTON, of Chicago, in the county of Cook and State of Illinois, have invented certain new and useful Improvements in Tools for Facing Emery-Wheels; and I do hereby declare that the following is a full, clear, and exact description of the invention, which will enable others skilled in the art to which it appertains to make and use the same, reference being had to the accompanying drawings, and to letters of reference marked thereon, which form a part of this specification.

One of the great difficulties to be overcome in the use of emery-grinding wheels is the removal from their grinding-surfaces of a glaze which is formed by small particles of metal and grease, and the keeping of the grinding-surfaces thereof "sharp," so that it will "cut."

The object of my invention is to provide a tool to overcome the difficulties above set forth, and which will, moreover, be useful in turning the periphery of the emery-wheel when from use or other cause it has become worn away more in one place than another. This I accomplish by a number of spur-wheels or steel disks, or both conjointly, arranged at an angle to each other on a shaft adjustable in a suitable head, from which latter extends a handle.

In the drawings, Figure 1 is a side elevation. Fig. 2 is an end or face view. Figs. 3 and 4 are detail views. Fig. 5 is a perspective view, and Fig. 6 is a transverse section, on the line 35 *xx* in Fig. 1.

In the drawings, A represents a head having downwardly-projecting fingers *a a*, and having longitudinal slots *b b* and *c*. Slot *c* is the central slot, and divides the head vertically, and slots *b b* are placed one on either side of slot *c*; and at an angle thereto at right and left declination, respectively.

Passing laterally through the head A, and intersecting the slots *b b* and *c*, is an aperture, *d*, in which is placed a loose pin or shaft, B, preferably of a length a little less than the lateral dimensions of the head. In order to prevent this shaft B from working or falling out, I close the side openings of the aperture *d* 50 by small circular plates *e*, pivoted and held

in position by the screw *e'*. Placed within the slots *b b*, and journaled on said shaft B, are steel disks C, (two being placed in each slot,) having a central aperture, the diameter of which corresponds to the major axis of the ellipse they describe around the shaft B; and journaled on the shaft within the central vertical slot, *c*, is a spur-wheel, D. These disks and spur-wheels have their engaging-surfaces on about the same vertical plane. Extending 60 from said head A is a suitable handle, G, by which my invention is manipulated.

In using my improved tool the fingers are placed over and ride upon the crest of a suitable tool-rest, thus serving as the fulcrum, so 65 that by raising or lowering the handle the cutting and scraping devices—viz., the spur-wheel and disks—are advanced or withdrawn from the periphery of the emery-wheel it is facing or truing. When in contact with the 70 rapidly-revolving emery-wheel, the disks and spur-wheel acquire a speed of very many thousands of revolutions a minute. Thus the spur-wheel acts as a rotary pick, striking the periphery of the emery-wheel with such force as to 75 break away small particles of emery, and roughen or (what is known to the trade as) "sharpen" the same, so as to promote its "cutting" ability. The engaging-surface of the disks, being at an angle to the perpendicular 80 motion of the said emery-wheel, creates a scraping and cutting effect, thus removing the "glaze"—viz., the accumulation of grease and emery and metal dust—on the grinding-surface of the wheel, which, unless it is removed, 85 impairs its grinding capacity.

It is known to me that there are tools now in use for facing emery-wheels, having alternate disks and spur-wheels placed vertically or at right angles on a shaft; but in these tools 90 the ability to operate, as above set forth, depends upon the power the operator can exert to press the same against the wheel, and at the same time move it to the right and left alternately. In this tool the disks have only a 95 straight perpendicular cut, rendering the lateral motion absolutely necessary, and, moreover, when being moved laterally to one side or the other the disks and spur-wheels acquire an almost imperceptible obliqueness to its 100

shaft in the direction of the lateral motion of the tool, which it is very difficult to overcome without removing it from contact with said wheel. These objections are overcome 5 by my improved tool, which has the disks placed at the same angle in contrary directions on either side of the central and vertical spur-wheel, so that they counteract upon each other, very little effort of the operator being necessary to move it one direction or the other without removing it from contact with the emery-wheel.

I do not wish to be understood as limiting myself to the alternate use of disks and spur-wheels, for either spur-wheels or disks alone for some classes of work may be preferable. Moreover, it is obvious that the shaft B may be bent, so as to be at right angles to the inclined cutting devices, without departing from 20 the spirit of my invention; but

What I claim as new, and desire to secure by Letters Patent, is—

1. In an emery-wheel-facing tool, the combination, with a central and perpendicular spur-wheel, of steel disks arranged on either 25 side of the same, preferably on the same shaft, and at an angle thereto of right and left declination, respectively.

2. An emery-wheel-facing tool consisting of a head, A, handle G, extending from the same, fingers *a a*, projecting downward from said head, and slots *b b* and *c*, made longitudinally therein and at an angle to each other, shaft B, intersecting said slots, and disks C and spur-wheel D, placed within said slots and on said 30 shaft, substantially as set forth.

In testimony that I claim the foregoing as my own I hereunto affix my signature in presence of two witnesses.

JOSEPH D. HUNTINGTON.
